COMBUSTION ENGINE

Friedrich Sasse, Berlin, and Ernst Daiber, Lichterfelde-West, Germany, assignors to General Electric Company, a corporation of New York

Application May 11, 1934, Serial No. 725,024
In Germany July 12, 1933

3 Claims. (Cl. 123—139)

The present invention relates to combustion engines, especially to engines of the Diesel type with airless fuel injection comprising a plurality of cylinders to which fuel is supplied by means of fuel feeders actuated by the pressure within the cylinders. The feeders receive the fuel by pumping means which may be a single pump or preferably a pump for each cylinder.

Difficulties are experienced with such engines when fuel is supplied simultaneously during a certain period of a cycle to all feeders because due to the simultaneous supply of fuel to all feeders the fuel supply to one or more of the feeders takes place during the period of the compression stroke in the cylinder, that is, when the fuel feeder is subjected to a high pressure. The pump or pumps supplying fuel to such feeder or feeders would have to overcome the pressure on the feeder by the corresponding cylinder. This drawback could be overcome by the provision of special pumping means, for example, stronger pumps with respect to those cylinders in which the fuel supply to the corresponding fuel feeders takes place during a period of high pressure within said cylinders.

The object of our invention is to provide an improved construction and arrangement for combustion engines of the type specified above whereby like pumping means for all cylinders may be operated simultaneously. This is accomplished in accordance with our invention by the provision of special storing devices connected between the pumping means and the feeders of those cylinders in which high pressure exists during the compression stroke of the pump means.

For a better understanding of what we consider to be novel and our invention, attention is directed to the following description and the claims appended thereto in connection with the accompanying drawing which forms a part of our specification.

In the drawing, Figs. 1 and 1a are diagrammatic illustrations of combustion engines embodying our invention; Fig. 2 is a diagram illustrating the operation of a combustion engine of the type referred to above; and Fig. 3 is a somewhat diagrammatic view showing more in detail the arrangement according to our invention.

The combustion engine in Fig. 1 comprises six cylinders I, II, III, IV, V and VI. Fuel is supplied to the cylinders by pumping means including a fuel pump 10 for each cylinder. All six fuel pumps are driven by a common drive means 11 which may be an eccentric or a cam on the crank shaft 55 of the engine. Connected between each cylinder

and the pumps 10 are fuel feeders 12 connected to the cylinders by conduits 25. In accordance with our invention we provide in the present example between the pumps 10 and the fuel feeders 12 of the cylinders I and III storing devices 13 which will be described fully hereinafter. The storing devices 13 are connected to the pumps by conduits 50 and to the fuel feeders by conduits 55.

Fig. 1a illustrates a similar arrangement as 10 that of Fig. 1. Like parts in Fig. 1a therefore are designated by like reference characters primed. The only distinction between the arrangements of Figs. 1 and 1a is that whereas the arrangement of Fig. 1 includes a separate fuel pump 10 for each cylinder, the arrangement according to Fig. 1a includes a pump 10' for compressing fuel for more than one cylinder.

Referring now to Fig. 2, which shows a working diagram of such a six-cylinder engine under 20 the assumption that it is a four-cycle engine in which a complete cycle in each cylinder is performed during two complete revolutions or 720 angular degrees of the crank shaft, the curves 14 represent the pressures in the individual cylinders of the engine. The numbers I to VI of the cylinders are indicated below the abscissae near the peaks of the corresponding pressure curves. Thus the diagram shows, for example, that the pressure for cylinder III reaches a maximum at 30 about 150 angular degree position of the crank shaft. As pointed out above, fuel is injected in the cylinders by fuel feeders subject to the pressure in the cylinders. In a four-cycle engine the fuel supply then takes place during the air 35 compression stroke in the cylinder, that is, shortly before the pressure in the cylinder reaches a maximum. The fuel supply to the cylinders is indicated in the diagram by crosshatched surfaces 15. The fuel supply to cylinder III, for 40 example, takes place approximately between 90 and 140 angular degree positions of the crank shaft, whereas, the fuel supply to cylinder IV takes place between 330 and 380 degree angular 45 positions of the crank shaft. The compression or discharge stroke of all six pumps being driven by a common drive member takes place during the first 150 degrees of the indicated cycle. The simultaneous fuel discharge periods of the pumps is illustrated by a single crosshatched surface 50 15a. As the diagram clearly brings out, the actuation of the feeder, that is, the supply of fuel from the feeder to the cylinder with respect to cylinders I and III, also takes place during the first 150 degree period of the cycle. Hence,

55

with an ordinary arrangement the fuel supplied by the pumps 10 for cylinders I and III would have to overcome the pressure exerted on the fuel feeder by the air compression within said cylinders. As stated in the beginning, this could be done by the provision of stronger pumps, in the present instance with respect to cylinders I and III. According to our invention this is accomplished by the provision of special storing means 13 (Fig. 1) between the pumps 10 and the fuel feeders 12 of the cylinders I and III.

Referring now to Fig. 3, which shows more in detail the combustion cylinder I with its fuel metering pump 10, its feeder 12 and the storing means 13 between the feeder and the pump. The different elements of the engine are united by a casing 16. The cylinder I has a piston 17. Provided in a head 18 for the cylinder is an injection valve 19 having a valve member 20 biased in downward direction by a compression spring 21. A lower portion 22 of the movable valve member 20 is reduced in diameter, forming a shoulder 23. The portion 22 and the valve casing form an annular chamber 24 connected to the fuel supply pipe 25. The supply of fuel under pressure by the pipe 25 to chamber 24 effects upward movement of the valve member 20 against the biasing force of the spring 21 and permits the injection of fuel into the cylinder through a nozzle member 26. The other end of the pipe 25 is connected to the fuel feeder 12, which latter comprises a casing 27 and a differential piston 28. The reduced portion of the latter projects into a fuel chamber 29 and the lower portion of the differential piston projects into a chamber 30 and is biased in upward direction by a spring 31. The chamber 30 communicates through a pipe 32 with the compression space of the cylinder. Thus the differential piston 28 is biased upward by the resultant force of the spring and the pressure in the combustion space. Assuming the chamber were filled with fuel, this fuel is forced through the pipe 25 and injected through the nozzle 26 into the cylinder during the air compression period of the cylinder. The injection stroke begins at a certain pressure in the cylinder and ends when the differential piston has reached a certain upper position.

The fuel pump 10 comprises a piston 33 having a lower block member 34 provided with a roller 35, which latter engages the drive member 11, in the present instance indicated as a cam 36 secured to a crank shaft 37 of the engine. The roller is held in engagement with the cam 36 by a biasing spring 38. The piston projects into a pump chamber 39 defined by the pump casing. Connected to this chamber is a discharge valve 40 biased towards closed position by a spring 41 and a combined inlet and relief valve 42 for connecting and disconnecting the compression space 39 with a fuel conduit 43. The suction and relief valve 42 includes a movable member 44 biased in downward direction by a spring 45 and adapted to be opened by a member 46 pivotally connected to a lever 47. The latter has a left-hand portion held on an adjustable eccentric 48 and a right-hand portion projecting into a slot 49 of the block member 34.

The operation of the pump is as follows: During downward movement of the pump piston 33 a vacuum is created in the chamber 39, effecting opening of the suction valve member 44 whereby fuel is supplied from the conduit 43 into the chamber 39. As then the pump piston is forced upward, causing compression of the fuel in the

chamber 39, the valve member 44 is closed and at a certain pressure in the chamber 39 the discharge valve member 40 is opened, permitting the discharge of fuel through the discharge conduit 50. The flow of fuel from chamber 39 to conduit 50 is interrupted at a certain point by the opening of the valve member 44 acting then as a relief valve. The opening of this member is accomplished by the upward movement of the lever 47 which in a certain position causes the member 46 to force the movable member 44 upward whereby the pressure in the compression chamber 39 is relieved, the remaining fuel flowing back into the supply conduit 43 and permitting closing of the discharge valve 40. Connected between the pump, more particularly the discharge conduit 50 thereof, and the fuel feeder 12 is the fuel storing device 13. This device comprises a casing 51 forming a storing chamber 52 and having a piston 53 disposed within the chamber. The piston is biased in upward direction by a spring 54. The chamber 52 is connected to the fuel feeder 12 by the conduit 55 and a check valve 56, preventing backward flow and permitting the flow of fuel from the chamber 52 to the chamber 29 of the fuel feeder when the pressure in the chamber 52 is greater than the pressure in the chamber 29 of the fuel feeder. The check valve 56 is normally biased towards closing position by a spring 57. As pointed out above, such fuel storing device 13 is provided for each cylinder I and III with respect to which the fuel injection falls within the period of the fuel supply to the fuel feeders 12 by the corresponding pumps 10.

During operation the fuel compressed and discharged by the pump 10 through the discharge conduit 50 is supplied to the chamber 52. The piston 53 of the storing device thereby is forced downward against the biasing force of the spring 54. The check valve 56 remains closed because during this period it is subjected to the biasing force of the spring as well as the pressure in conduit 55, this pressure being high during this period due to the upward movement of the differential piston 28 of the fuel feeder. A short period of time after the termination of the fuel injection to cylinder I, the pressure in the cylinder decreases, causing a decreasing biasing force on the lower side of the differential piston 28 and permitting the latter to move downward, causing a reduced pressure in the chamber 29 of the fuel feeder. This reduced pressure permits opening of the check valve 56, the fuel contained in the storing chamber 52 then being forced into the feeder chamber 29 under the action of the spring biased piston 53. Thus, it will be readily seen that the fuel supplied by the pump 10 is stored for a certain period of time in the storing device 13, whence it is supplied to the fuel feeder 12 after the termination of the fuel injection to the cylinder I. The fuel supply arrangements for the cylinders I and III are alike and also the fuel supply arrangements for the cylinders II, IV, V and VI, respectively, the latter differing from the arrangements for cylinders I and III in that they do not include a storing device 13. In this case the discharge conduits 50 communicate directly with the chambers 29 of the corresponding fuel feeders 27, as indicated in Fig. 1.

With our invention we have provided an improved arrangement for combustion engines in which all cylinders are provided with like pump means and the fuel discharged from the pump means is stored at a comparatively low pressure in a storing device for certain cylinders. The

arrangement may be such that the spring 54 of the storing device is so dimensioned that the piston 53 may be moved by a pressure of 60 atmospheres, whereas 250 atmospheres are necessary to open the injection valve or nozzle 23. Hence the pump means has to be designed for 60 atmosphere pressure instead of for 250 lbs. pressure.

Having described the method of operation of our invention, together with the apparatus which we now consider to represent the best embodiment thereof, we desire to have it understood that the apparatus shown is only illustrative and that the invention may be carried out by other means.

15. What we claim as new and desire to secure by Letters Patent of the United States, is:

1. In a multi-cylinder internal combustion engine, a plurality of engine cylinders, a fuel metering pump for each engine cylinder, the pumps being arranged to discharge fuel simultaneously, means associated with each engine cylinder for injecting the fuel discharged by the corresponding fuel metering pump to said engine cylinder comprising a fuel feeder actuated by pressure variations in said engine cylinder and connected between said engine cylinder and said corresponding fuel metering pump, and a fuel storing device connected between the fuel feeder and the corresponding fuel metering pump of those engine cylinders whose fuel injection period falls within the period of fuel discharge from its fuel metering pump, whereby the discharge from said metering pump is stored in said storing device during the injection period and is forced into the feeder after the injection is terminated.

2. In a multi-cylinder internal combustion engine, a plurality of engine cylinders, fuel pumping means for the cylinders for compressing and discharging fuel during a definite period of a complete operating cycle of the engine, means associated with each cylinder for simultaneously

receiving fuel from the pumping means and discharging the fuel to the corresponding engine cylinder, said means comprising a fuel feeder actuated by pressure variations in said engine cylinder and connected between said engine cylinder and the fuel pumping means, and a fuel storing device connected between the fuel feeder and the pumping means of those engine cylinders whose fuel injection period falls within the period of fuel discharge from the pumping means whereby the discharge from the pumping means is stored in said storing device during the injection period and is forced into the feeder after the injection is terminated.

3. In a multi-cylinder internal combustion engine, a plurality of engine cylinders, a fuel metering pump for each engine cylinder, the pumps being arranged to discharge fuel simultaneously, means associated with each engine cylinder for injecting the fuel discharged by the corresponding fuel metering pump to said engine cylinder comprising a fuel feeder actuated by pressure variations in said engine cylinder and connected between said engine cylinder and said corresponding fuel metering pump, and a fuel storing device connected between the fuel feeder and the corresponding fuel metering pump of those engine cylinders whose fuel injection period falls within the period of fuel discharge from its fuel metering pump, whereby the discharge from said metering pump is stored in said storing device during the injection period and is forced into the feeder after the injection is terminated, the fuel storing device comprising a chamber communicating with the pump, conduit means including a check valve between the chamber and the feeder and a spring pressed piston for forcing fuel from the chamber into the feeder.
